BOTTLE STOPPER ADJUSTING MEANS

Louis Illmer, Cortland, N. Y.

Application March 7, 1940, Serial No. 322,832

8 Claims. (Cl. 120—57)

This invention broadly relates to freely removable closure means for mouthed wells or the like receptacles, and more particularly pertains to a manipulative ink bottle stopper provided 5 with an adjustably controlled quill, brush or other applicator by which drawing ink or the like fluid may without inundation, be transferred in measured quantities between the twin points of a draftsman's ruling pen or the like implement.

10 When cross hatching or otherwise drawing a series of fine shade lines, an experienced draftsman usually charges his ruling pen to a precise initial fill of India ink without flooding to maintain a desired line heft and obviate the need for 15 repeatedly readjusting the pen point spacing after each fill. To facilitate rapid productive work of this kind, it is herein contemplated to selectively uphold the applicator dip into the prevailing ink level to a predetermined depth by the use 20 of adjustable guard bar means preferably carried by the stopper as a unit. Such means are neatly installed exteriorly of the bottle confines and manipulatively interposed between the bottle neck and a stopper grip portion without defiling 25 the fingers with ink.

Should a normally transparent glass bottle be rendered opaque by its black ink contents, the position of such guard bar visualizes the dip depth to which the quill may have been set. My 30 stopper control is intended to be sold with each ink bottle as a commodity unit, but the same underlying adjusting principle may likewise be incorporated into a cooperating stand adapted to 35 gripplingly mount a conventional draftsman's ink bottle thereon.

A certain minimum dip depth is required to deliver a requisite fill charge into a ruling pen and the extent of this charge may be conveniently altered by a corresponding bar adjustment whereby to successively draw a line of one and the same heft after each replenished pen fill. A similar bar control suffices to limit the dip when applied to an artist's brush for uniformly washing a 45 drawing with India ink or the like tints.

The object of the present improvements is to devise a simple adjustable stopper appurtenance of the indicated character capable of maintaining an applicator at a substantially predetermined dip beneath the fluid level prevailing in a mouthed receptacle and which appurtenance shall be adapted for low cost fabrication on a rapid productive basis including the use of 50 moulded plastic parts.

55 Alternative structural embodiments of such stopper means are exemplified in the accompanying one sheet of drawings, in which:

Fig. 1 cross-sectionally represents an elevation- 60 al view of a drawing ink bottle provided with a

stopper unit equipped with my dip control bar, and Fig. 2 is a top view thereof.

Fig. 3 details a stopper section taken along 3—3 of Fig. 2.

Figs. 4 and 5 fragmentally depict an exterior 5 view and a partial sectional view of a modified style of stopper guard bar.

Fig. 6 cross-sectionally illustrates still another 10 style of dip control in which adjustable bar means are carried by an associated bottle stand, 15 and Fig. 7 is a top view thereof with the bottle removed.

Referring more specifically to Figs. 1 to 3, the 20 numeral 10 denotes a mouthed conventional ink well or bottle commonly used by draftsmen for filling ruling pens with India drawing ink or the like fluid whose initial level when full is indicated by 11. Said shallow bottle is preferably of the usual small size that can be conveniently grasped in one hand and its stopper 25 unit 12 manipulated in the other hand for pen filling purposes. The access mouth 13 of such bottle is generally flared outwardly to provide for a divergent conical contour and which bottle when not in use, is tightly sealed by a mated stopper against fluid evaporation or spill.

Said stopper unit is herein kept bodily demountable and preferably comprises a crown cap consisting of a stanchion component 14 of 30 which the base may be diametrically enlarged to constitute a knurled grip or rim component 15. The rim bottom face may be countersunk at 16 for the centered reception of the cemented tapered cork agency 17 or the like yieldable sealing material. The integral cap parts 14 and 35 15 are designed to be die moulded from Bakelite, vulcanized rubber compound or the like plastic and the cork may be equipped with the usual depending quill or applicator 18.

After a tightly sealed cork has been withdrawn from the stopper mouth by finger twisting the rim 15, the stopper may by gripping its stanchion 14 be loosely reinserted as shown and its quill immersed to a predetermined dip depth 40 D below the prevailing ink level 11, there being an adjustable guard bar interposed to maintain such depth in follow up fashion subsequent to the gradual lowering of the fluid level.

Opposed flattened sides of the cap rim 15 may 45 respectively be provided with a trunnion receiving aperture 20 and with a pair of faced pads each having a series of moulded kerfs or serrations 21 impressed therein that may be radially directed toward a contiguous aperture as in 50 Fig. 1. A ball shaped guard 22 of wire has the ends thereof turned to respectively trunnion in the aligned pintle apertures. Intermediate the length of each ball leg, such wire may be shaped to include one or more depending stop props 23 55

which ride upon the upturned neck shoulder 24 when my stopper is loosely entered into its bottle mouth. Said bail may further be provided with struck up V shaped tits 25 that selectively engage 5 with any one of several cap serrations. As a substitute for the balanced stop props, the medial bail region may be made to serve a like purpose.

When the bail is manipulatively depressed into its full lined position, the entered cork 17 will be 10 held raised to fix the quill depth D, but when the bail is adjustably shifted into its topmost dotted position, the cork may descend to bring about a corresponding augmented quill dip and allow the cork to be tightly seated into the bottle neck. 15 In this embodiment, the capped cork and its adjusted guard linkage are kept bodily removable from the bottle as a unit, and thence transferred to a ruling pen to fill the same with a measured ink charge that is dependent upon the setting 20 given to the bail 22.

Referring now to Figs. 4 and 5, the stopper unit 30 is similarly provided with a moulded crown cap comprising a knurled grip rim component 31 and a stanchion component 32, the latter being 25 preferably transversely slotted at 33. The rim perimeter may be oppositely recessed as at 34 and have a spring actuated detent 35 inserted into a suitable cap socket. The bottom face of said cap may be countersunk for the reception of the 30 tapered cork 36.

In this instance, the guard bar 37 is fabricated from corrugated metallic strip stock and is preferably given a U-shaped contour of which the respective legs are slidably nested within a contiguous guide recess 34, the guard yoke being 35 slidably entered through the slot 33, as shown. By adjustably depressing or raising this bar yoke into a different retained position, the depending cork quill will be selectively shifted into an altered 40 dip position to follow up the ink level as the supply gradually becomes depleted and thereby substantially maintain a constant charge for transfer to the ruling pen. When the ink supply reaches a level too low for an adequate quill 45 charge, the bottle may be refilled and the bar appropriately readjusted to prevent pen flooding.

The use of moulded plastic together with strip stock components serves to hold down fabrication cost to a degree that allows of incorporating my 50 adjustable guard appurtenances to stoppers for drawing ink bottles as a unit without necessitating a substantial increase in the retail selling price thereof.

Figs. 6 and 7 disclose a supplementary bottle 55 base 39 of moulded plastic, preferably vulcanized rubber compound comprising a substantially round foot plate 40 including checkered pad faces 41 designed to firmly rest upon a normally inclined drawing table without slip. Within such 60 plate margin there is die cast, a substantially endless bottle centering flange preferably shaped to comprise perimetricaly spaced but laterally yieldable jaws such as 42 of which the upstanding bore face may be undercut as at 43. Such flange 65 spacing facilitates the insertion or removal of a gripped bottle.

Adjoining one such jaw is a tubular post or boss 44 which may have moulded therein an inbuilt metallic U-shaped strip 45 provided with opposed 70 closely spaced corrugations or teeth such as 46 and 47. Telescopically cooperating with such teeth is an extensible standard or prop 48 also shaped from strip stock of which the upper prop end may terminate in a return bend loop that 75 mounts the hinge pintle 49 therein. Each super-

imposed lower twin end of such strip stock is respectively shown corrugated to adjustably engage with and be retained by said teeth 46 and 47 and thereby allow the pintle to be manipulatively raised or lowered stepwise. The upper 5 end of the standard may be offset to provide for a ledge 50. Pivoted to said pintle is a leverized guard bar 51 which may be provided with a stop lug 52 adapted to rest upon said ledge when the guard bar assumes its full-lined operative position 10 beneath the stopper cap rim 60. Such lever may be swung in the arrowed direction but if desired may also be rigidly affixed to said standard. By squeezing the spaced prop corrugations together, they may readily be disengaged from their mated 15 teeth to adjust the dip D'.

It will be obvious that the function of the adjustable guard lever 51 is identical with the corresponding members 22 and 37 previously described. As indicated in Fig. 6, the stopper cork 20 53 may be tubular and have a cylindrical ferrule 54 of an artist's brush, snugly entered there-through. The tip of the brush bristles 55 then adjustably dip into the bottled fluid 56 to an extent D' as fixed by the prop adjustment and a 25 brush handle length 57 may extend outwardly through the stopper stanchion 58, as shown.

As an understructure, the one-piece base plate 39 stabilizes the shallow bottle 59 against upset, and is particularly useful where ink containers 30 of this kind need to be shiftably placed within the confines of a large sheet that is being drawn upon.

Should a loosely stoppered ink bottle rest upon a sharply inclined drawing table, it is preferred 35 to provide my base foot flange 40 with apertures such as 61 or with inset slots such as 62 or the like through which a thumb tack may be entered into engagement with an underlying drawing board, thus further stabilizing said bottle against 40 inadvertent upset. As an inherent attribute of my flange when moulded from rubber compound, a tack may also penetrate therethrough without any special aperture provision.

Where the need for a measured applicator dip 45 is of no significance, the forked guard lever 51 may be thrown into its inoperative position 51', it being emphasized however that by virtue of my telescopic prop 48, the cork can readily be pressed home to seal the bottle mouth against 50 leakage without necessarily throwing said lever into its 51' position. It will be evident that my bottle base 39 may also be utilized in conjunction with the Figs. 1 or 4 style of stopper without resort to any telescopic prop such as 48.

As will be understood by those skilled in this art, the disclosed guard bar features are likely to find application to purposes other than drawing ink bottles and that various modifications in the structural details thereof may be resorted 60 to in likewise carrying out the same underlying principles, all without departing from the spirit and scope of my invention herein described and more particularly defined in the appended claims.

I claim:

1. In a liquid containing receptacle having an outwardly flared mouth, a bodily demountable stopper unit comprising a substantially conical corking agency fitted to seal said mouth when 70 fully closed and the divergent end confines of which agency has affixed thereto a crown cap that radially overhangs such divergent confines, an applicator depending from the converging end of said agency and dipping into the contained liquid to a predetermined depth when the stopper 75

is loosely entered into said mouth, and manipulatively adjustable guard means disposed to engage beneath the crown cap and selectively sustain said loosely entered stopper whereby to control the dip of the applicator into said liquid.

2. In a liquid containing receptacle having an outwardly flared mouth including exteriorly disposed shoulder means, a bodily demountable stopper unit comprising a substantially conical 10 corking agency fitted to seal said mouth when fully closed and the divergent end confines of which agency has affixed thereto a crown cap that radially overhangs such divergent confines to spacedly overlie said shoulder means and 15 which cap is equipped with a series of serrations, an applicator depending from the converging end of said agency and adapted to dip into the contained liquid to a predetermined depth when the stopper is loosely entered into said mouth, and 20 manipulatively adjustable guard means carried by said cap and arranged to selectively engage with and be retained by a selected serration, a portion of said guard means thrusting against said shoulder means to sustain the loosely entered 25 stopper and definitely fix the dip of the applicator into said liquid.

3. In a liquid containing receptacle having an outwardly flared mouth including exteriorly disposed shoulder means, a bodily demountable 30 stopper unit comprising a substantially conical corking agency fitted to seal said mouth when fully closed and the divergent end confines of which agency has affixed thereto a moulded crown cap of plastic material providing for a grip 35 rim that radially overhangs such divergent end confines in spaced relation to said shoulder means and opposed faces of which rim are each provided with a series of serrations and a contiguous trunnion receiving aperture, and manipulatively 40 adjustable guard means trunnioned to swing about such apertures and to thrust upon said shoulder means when the corking agency is loosely entered into said mouth, said guard means being arranged to selectively engage certain of said 45 serrations to regulatively fix the spacing between the divergent end of the corking agency and said shoulder means.

4. In a liquid containing receptacle having an outwardly flared mouth including exteriorly disposed shoulder means, a bodily demountable 50 stopper unit comprising a substantially conical corking agency fitted to seal said mouth when fully closed and the divergent end confines of which agency has affixed thereto a crown cap including a transversely slotted stanchion component whose base is diametrically enlarged to constitute a grip rim that extends radially beyond such divergent end confines to overlie said shoulder means and which rim has opposed guide recesses therein, manipulative U-shaped guard bar means of which the yoke is entered through the stanchion slot with the legs thereof slidably mounted in the respective guide recesses, and releasable retaining means for selectively setting the guard bar means into different positions of adjustment lengthwise of said stanchion component.

5. In a liquid containing bottle having an outwardly flared mouth including exteriorly disposed shoulder means, a base plate provided with centering flange means embracingly gripping the

bottom region of said bottle therein, a freely demountable stopper comprising a substantially conical corking agency fitted to tightly seal said mouth when fully closed and the divergent end confines of which agency has affixed thereto a 5 crown cap that spacedly overhangs said shoulder means, an applicator depending from the convergent end of said agency to dip into the liquid contained in such bottle when said agency is loosely entered into the mouth thereof, an extensible 10 prop erected upon said base to terminate in guard bar means that engage beneath the crown cap and serve to selectively uphold the loosely entered stopper, and releasable adjusting means retaining the extensible prop to an adjusted length.

6. In a liquid containing bottle having an outwardly flared mouth circumscribed by a shoudered neck, a moulded base plate of plastic material provided with an integral centering flange that grippingly stabilizes the bottom of said bottle against upset, a freely demountable stopper comprising a substantially conical corking agency fitted to tightly seal said mouth when fully closed and the divergent end confines of which agency has affixed thereto a crown cap that radially 20 overhangs such confines and spacedly overlies the neck shoulder, an applicator depending from the convergent end of said agency to dip into the liquid contained in such bottle when said agency is loosely entered into the mouth thereof, and manipulatively adjustable guard bar means extending into said spacing between the crown cap and said shoulder to regulatively uphold the loosely entered stopper in different elevations 25 with respect to said base plate.

7. In a liquid containing bottle having an outwardly flared mouth circumscribed by a shoudered neck, a moulded base plate of plastic material provided with integral flange means that grippingly stabilizes the bottom region of said bottle against upset and which plate is further provided with upstanding boss means, a freely demountable stopper comprising a substantially conical corking agency fitted to tightly seal said mouth when fully closed, an applicator depending from the convergent end of said agency to dip into the liquid contained in such bottle to a predetermined extent when said agency is loosely entered in the mouth thereof, and adjustable guard bar means carried by said boss means and arranged to selectively sustain the applicator at different dip levels.

8. In a liquid containing bottle adapted to rest upon an inclined table and having an outwardly flared bottle mouth circumscribed by a shoudered neck, a moulded base plate of plastic material provided with integral flange means that grippingly stabilizes the bottom region of said bottle against upset, said flange being provided with tack receiving means and which tack when entered operatively engages said table, a freely demountable stopper comprising a substantially conical corking agency fitted to tightly seal said mouth when fully closed, an applicator depending from the convergent end of said agency to dip into the liquid contained in such bottle to a predetermined extent when the agency is loosely entered into said mouth, and adjustable guard bar means arranged to selectively sustain said applicator at different dip levels.

LOUIS ILLMER.
